UNITED STATES PATENT OFFICE.

LEON R. MACKENZIE, OF DES MOINES, IOWA.

APPARATUS AND METHOD FOR PAVEMENT CONSTRUCTION.

Application filed August 20, 1928. Serial No. 300,720.

The object of my invention is to provide an improved apparatus and method for pavement construction wherein an asphaltic road or wear course having a substantially shallow depth may be placed upon a concrete base and so united together that the asphaltic material forming the wear course will be anchored to its base at points arranged at angles to each other and will be constrained 10 against movement from its base and thereby eliminating ridges and hollows in the surface of the wear course.

Still a further object is to provide a novel platform mold adapted to be temporarily supported upon a freshly laid concrete base and vibrated or rolled over by a roller for compacting the wet concrete and at the same time molding in the upper surface thereof a plurality of specially shaped grooves arranged transversely to each other and in communication with each other.

It is well known that in the preparation and laying of a concrete base for asphalt road or street construction, it is desirable to use a 25 large amount of rock aggregate in proportion to the cement mortar for the reason that rich mortar mixtures are more susceptible to extreme expansion and contraction under changes of temperature, and the pavements 30 are therefore much more susceptible to heaving of the base, which will also heave or otherwise displace the asphaltic wear course.

Likewise high mortar concretes are extremely susceptible to absorption of moisture 35 as compared with concrete containing a high stone content. The absorption of moisture tends to disintegrate the structure of both the base and the asphaltic wearing course and particularly, by forming a sweat coat or film of moisture on the top of the concrete base 40 directly in contact with the asphaltic wear course, the bond between the top and the base is broken and the asphaltic wearing surface will break up as a consequence.

Concrete mixtures carrying a large proportion of coarse aggregate will not work easily under ordinary methods. Therefore 45 it is necessary in order to make such mixture applicable for forming a proper and uniformly grooved concrete base to provide especially constructed apparatus in the form of platforms or the like, which are laid upon the mixture and then subjected to such treatment as will impress the platforms or apparatus 50 into the concrete and equally and uniformly

distribute the mortar relative to the rock aggregate.

By providing platform molds having specially designed groove forming projections on their under side, I am able to force the 60 platforms downwardly relative to the concrete, and thereby the concrete or plastic material is densified, and at the same time there is molded in the concrete surface a substantially uniform pattern of projections and 65 grooves.

Still another object is to provide grooves upon the upper surface of the concrete base, which grooves are arranged in such manner relative to the line of traffic and relative to 70 each other and at the same time are provided with downwardly converging sides, so that a cross section of each groove is substantially V-shaped with the lower half of the V cut off to provide a horizontal base in the bottom of 75 each channel groove, wherein the wear course laid thereover is anchored to the base to meet the forces exerted by traffic from any direction.

Still another object is to provide platforms 80 adapted to be fabricated by use of a plurality of metal sheets preferably of stamped material for forming projections thereon, which when inverted and laid upon the plastic concrete will form the necessary grooves therein, 85 the corrugated and formed-up plates being connected together in sections by stringers, each hollow portion between any pair of the projections being provided with insert cleats for separating the hollow portions into vari- 90 ous sections so that when the platform is placed upon a plastic base the surface thereof will be arranged with grooves extending in at least two different directions with the walls of the grooves formed in the plastic material 95 being inclined upwardly and outwardly from the main body portion of the plastic base.

Another object is the formation of a platform mold wherein corrugated metal plate for forming a portion of the platform base is 100 filled with filler blocks.

More particularly, it is my object to provide a molded top surface on the concrete base having projections and channel grooves therein spaced a sufficient distance apart and 105 so proportioned that when the asphaltic material is spread thereover and compressed, there will be no shrinkage or increase in the material after the wear course of asphaltic material has been applied and completed. 110

Still another object is to arrange the side walls of the channel grooves at an angle so that when asphaltic material is placed thereover, raked and fluffed and then rolled, a certain amount of the asphaltic material will be forced into the channel grooves and base and the side walls of the channel will impart a downward and sidewise force to the asphaltic material while under compression from above, the inclined side walls compensating for the difficulty in uniformly compressing asphalt of different thicknesses.

With these and other objects in view, my invention consists in the construction, arrangement and combination of the various parts of my apparatus and in the practice of my method, whereby the objects contemplated are attained, as hereinafter more fully set forth, pointed out in my claims, and illustrated in the accompanying drawings, in which:

Figure 1 is a top plan view of a portion of a concrete pavement base with a plurality of platform molds mounted thereon, illustrating the channel-shaped grooves formed in the upper surface of the base.

Figure 2 is a perspective sectional view taken on the line 2—2 of Figure 1, showing a portion of the concrete base with the groove forming platform placed thereon, the grooves after the platform has been removed, and a portion of the plastic wear course laid upon the concrete, thus illustrating the complete pavement construction.

Figure 3 is a transverse, enlarged, sectional view through one of the platforms and the concrete base taken on the line 3—3 of Figure 1, the platform being shown raised and away from the base.

Figure 4 is a sectional view showing the groove forming projections on the platform.

Figure 5 is a top plan view of the under side of one end of the platform for forming grooves in the upper surface of the concrete base.

Figure 6 is a view of the under side of a platform of slightly modified construction; and

Figure 7 is a detail, enlarged, sectional view taken on the line 7—7 of Figure 6.

The drawings filed herewith illustrate one way in which my method for pavement construction may be carried out.

In road and pavement construction, it is usually necessary to prepare the dirt sub-base 10, so that it is in substantially a smooth surface condition adaptable for receiving the concrete base.

A concrete mass 12 forms the concrete base upon the sub-base or soil 10. The base 12 may vary in thickness depending upon the strength desired for the pavement and the particular location of the road and the traffic it will carry.

It is desirable in a concrete base to provide

a considerable amount of rock aggregate. After the mixed cement, sand and rock aggregate forming the mass is laid on the sub-soil or base 10 and raked and leveled to a true specified contour, I find that the material may be condensed, and in order to condense the material, I provide platform molds A, which may be of various sizes and shapes, which platforms rest upon the upper surface of the freshly laid leveled concrete mass.

The platform molds are laid flat upon the upper surface of the mass and may be impressed into the mixture by the so-called vibrolithic method,—that is operating a vibrating machine upon the platform molds over the concrete mass.

Another way of condensing the concrete mass is to run a roller of sufficient weight over the upper surface of the platforms and cause them to be impressed, due to the weight so applied, into the concrete mass.

Still another way is to use the impact method of imparting a downward movement of the platform relative to the concrete mass.

In the drawings, the platform A is fabricated from a plurality of stringers 14 to which may be connected a metallic plate 16 formed into a corrugated sheet, so as to provide raised portions and recesses. The corrugated sheet 16 is secured to the stringers 14 in any suitable manner.

In order to give substantial strength to the metallic plate 16, I place filler blocks 18 on the under side of the ridges in the plate 16. The filler blocks also give a smooth upper surface to the platform molds between the stringers, so that mortar accumulation may be readily scraped or swept therefrom.

Between the ridges in the corrugated plate 16, there is necessarily formed a plurality of hollow portions or recesses 20. These recesses 20 run cross-wise of the plate 16.

It is desirable to have the completed concrete base upper surface provided with channel-shaped grooves running in more than one direction, and I therefore place small cleats 22 at spaced intervals in the hollow portions or recesses 20, so that there is formed a number of individual recesses.

The walls of each recess are inclined and converge towards each other and towards the base or bottom of the recess.

It will be noted that the upper surface of the plastic material or concrete base after the platforms are placed thereover with the plate 16 resting thereagainst that each recess in the platform will form an upstanding projection in the concrete base. Each upstanding projection is spaced from the others by channel-shaped grooves, which grooves in themselves have outwardly inclined side walls.

It thus follows that the distance between the upper edges of the projections in the concrete base is greater than the distance between the lower edges of the projections. Each re-

cess within the platform A forms a projection 24. For the purpose of further reference, the grooves or channels formed in the plastic material have been indicated by the 5 reference numeral 26. The ridges or projections in the plate 16 form the grooves 26 in the plastic material.

It will be noted that in Figures 4 and 5, the platform molds are provided with their ends 10 arranged at an angle relative to the stringers proper.

In Figure 6, which is a slightly modified form of structure, the ends of the platform are arranged at substantially right angles 15 to the stringers proper, although in this case, the recesses and ridges in the platform are still arranged at an angle relative to the stringers.

In the form of platform as shown in Figures 6 and 7 of the drawings, I place a sheet metal flat plate 28 upon the stringers and then place thereover a casting or the like 30, which is formed with a pair of cross ridges 32 and a number of ridges 34 arranged to run 25 lengthwise of the entire platform mold.

The ridges 32 and 34 define recesses 20 which are provided with converging side walls. The castings 30 which form the necessary grooves and ribs on the platform A are 30 anchored or fastened to the stringers 14 by bolts, screws or the like.

In the bottom of each recess 20, I provide a plurality of small openings 36 through which the water, air and small amounts of excess 35 cement mortar may pass during the process of impressing the platform in the upper surface of the concrete mass and forming in the upper surface of the concrete mass the necessary grooves and ribs as heretofore explained.

40 In Figures 4 and 5, the openings 36 are formed in the plate 16 proper, whereas in Figure 6, the openings 36 are formed in the separate plate 28.

The difference between the structure shown 45 in Figure 4 and the structure shown in Figure 6 resides in the fact that in Figure 4 the plate is formed of a single piece of material and corrugated and filler blocks are used for giving the device rigidity and strength, 50 whereas in Figure 6, a separate flat plate is used, which is connected to the stringers, and castings of any suitable kind are provided for giving to the platform mold the necessary raised projections and recesses.

55 Upon the completed concrete base, that is after the formation of ridges and channels in its upper surface, I then place upon such prepared base asphaltic material 38, which forms the wear course for the road.

60 It is well known that asphaltic material after it is laid upon a concrete base is spread out to substantially a uniform surface by being raked and fluffed. A roller is then used for compressing and condensing the fluffed 65 asphaltic material.

It is further well known that asphaltic material condenses more readily near its upper surface upon being rolled, than the lower portion, which is in contact with the base. It is desirable that the asphaltic material as 70 nearly as possible be compressed to the same density throughout its depth. It follows that when the asphaltic material is compressed, a certain amount thereof must be forced into the channels 26 in the concrete base. The fact 75 that asphaltic material compresses more readily near its upper surface means that more force is necessary to uniformly condense a thick section than a shallow section. My wear course is composed of both shallow and 80 thick sections.

The side walls of such channels being arranged on an inclined line and converging at their bottoms towards each other will tend to compel the asphaltic material which is received within such channels to be condensed so that the inclined walls or sides of each channel 26 impart a downward and sidewise force under compression from above to compensate for the difficulty of uniformly compressing asphalt of different thicknesses. 90

The openings or channels 26 in the base are wider than they are deep.

The ridges are so arranged relative to the channels in the platform mold, so that the 95 impressing of the projections on the platform mold into the plastic material is so proportioned that the forming of the channels in the base will compensate for the loss of air and excess water removed from the mass 100 during the impressing of the platform mold therein. The volume in the base displaced by the platform projections compensates for and is equal to the aggregate volume caused by loss of excess water and air, when the 105 platform mold is placed upon the base and impressed therein by pressure from above.

A certain amount of the material is compressed into the channels 26 and as the material is forced downwardly within such channels the inclined side walls of such channels tend to confine and restrict the asphaltic material so that the same density of the asphaltic material is had at a point where such material actually goes into the channels 26. 110

The asphaltic material or wear course 38 when laid over a concrete base prepared in the manner that I have just described is prevented from rolling or creeping because of the anchoring feature just mentioned. 120

The asphaltic material is locked or anchored to the concrete base in more than one direction. The channels are arranged at an angle relative to the line of traffic so that at no time is the traffic actually cutting or crossing the wear course at right angles to all of the points of anchorage of the wear course to the base.

I find that in the employment of my apparatus and method herein described that 130

it is desirable to so space and proportion the projections on the platforms forming the channels in the base and the recesses in the platforms forming the projections on the base, in such a relation to each other, so that there will be a compensation for the elimination of air and water in the concrete, so that there will be no shrinkage or increase in the concrete mass after my method has been employed.

The asphaltic material while it remains in contact with the concrete base is held against movement. On the other hand, when it is desired to cut through the entire pavement structure for the laying of sewers or the repair of sewers or the like, I find that after the asphaltic wear course has been cut, it can be raised from the base comparatively easily. By comparatively easily, I mean with less hours of labor than would otherwise be required if the channels had vertical sides therein instead of inclined sides, as I provide.

The term "asphaltic" as herein used is to denote bituminous mixtures, which are commonly used in connection with laying of pavements and the like. I do not necessarily intend to limit myself only to asphaltic material.

30. The term "platforms" as herein used is to denote an apparatus that is adapted to lie upon the wet concrete for forming and molding grooves and projections in the surface of the concrete base.

35. I claim as my invention:

1. A platform mold for pavement construction comprising a plurality of stringers, a plate secured to said stringers having a plurality of channels and ridges formed therein, a plurality of cross cleats mounted within said channels, for separating said channels into a plurality of sections, the walls of said channels being inclined from vertical whereby the platform mold when laid upon a plastic base will form channels therein having inclined walls with a plurality of ridges completely surrounded by said last channels.

2. A platform mold for pavement construction comprising a plurality of stringers, a plate secured to said stringers having a plurality of channels and ridges formed therein, a plurality of cross cleats mounted within said channels for separating said channels into a plurality of sections, the walls of said channels being inclined from vertical whereby the platform mold when laid upon a plastic base will form channels therein having inclined walls with a plurality of ridges com-

pletely surrounded by said last channels, and means for allowing the escape of air and water through said plate when the same is laid upon a plastic base.

3. A platform mold for pavement construction comprising a plurality of stringers, a plate secured to said stringers having a plurality of channels and ridges formed therein, some of the ridges running at angles relative to others, for separating said channels into a plurality of sections, the walls of said channels being inclined from vertical whereby the platform mold when laid upon a plastic base will form channels therein having inclined walls with a plurality of ridges completely surrounded by said last channels.

4. A platform mold for pavement construction comprising a plate, a plurality of parallel ridges on the under surface thereof and cross ridges extending between said parallel ridges.

5. A platform mold for pavement construction comprising a plate, a plurality of parallel ridges on the under surface thereof and cross ridges extending between said parallel ridges, said plate being provided with openings between the ridges.

6. A platform mold for pavement construction comprising a plate, a plurality of parallel ridges on the under surface thereof and cross ridges extending between said parallel ridges, said plate being provided with openings between the ridges, and stringers extending along said plate for reinforcing the platform mold.

7. A platform mold for pavement construction comprising stringers, a plate secured thereto, ridge members secured to said plate, said members comprising ridges extending in at least two different directions and connected together, the space between adjacent ridges being open, and openings in said plate co-incident with but smaller than the open spaces between said ridges.

8. A platform mold for pavement construction comprising stringers, a plate secured thereto, ridge members secured to said plate on the opposite side from said stringers and arranged at an angle relatively thereto, said members having walls, said walls being inclined from vertical, whereby the platform mold when laid upon a plastic base will form channels therein having inclined walls, the space between adjacent ridges being open, and openings in said plate co-incident with but smaller than the open spaces between said ridges.

LEON R. MACKENZIE.
